UNITED STATES PATENT OFFICE.

GEORGE G. FRYER, OF SYRACUSE, NEW YORK.

APPARATUS FOR INSERTING FILES.

No. 853,581.

Specification of Letters Patent.

Patented May 14, 1907.

Application filed November 30, 1903. Renewed October 18, 1906. Serial No. 339,575.

To all whom it may concern:

Be it known that I, GEORGE G. FRYER, of Syracuse, in the county of Onondaga and State of New York, have invented a certain 5 new and useful Apparatus for Inserting Piles, of which the following is a specification.

My invention has for its object the production of apparatus, particularly applicable for inserting piles into moist or submerged 10 soil, which is especially simple in construction and highly efficient in use; and to this end, it consists in the combinations and constructions hereinafter set forth and claimed.

In describing this invention, reference is 15 had to the accompanying drawing, in which like characters designate corresponding parts in all the views.

Figure 1 is a diagrammatic view, partly broken away, of a preferable embodiment of 20 my invention, the float being omitted. Fig. 2 is a vertical sectional view taken on line A—A, Fig. 1, a part of the end of the float being also illustrated. Fig. 3 is a vertical sectional view of a pair of detached interlocking divisions of the removable pile of my 25 apparatus. Figs. 4 and 5 are plan views of the opposing faces of the divisions seen in Fig. 3. Figs. 6 and 7 are elevations, partly in section, of the lower portions of modified constructions of the removable pile. Fig. 8 is a 30 elevation, partly in section, of the upper portion of said pile and a modified means for forcing the same downwardly. Fig. 9 is a plan view of a series of piles inserted by my apparatus, an overlying foundation being indicated by dotted lines.

The illustrated embodiment of my apparatus comprises a removable pile 1, means for facilitating handling of the pile, means 40 for forcing said pile into submerged unstable soil, means for facilitating the entrance of the removable pile into the soil, means surrounding the portion of the pile within the overlying water and containing a solidifiable material, means for solidifying the soil and the 45 solidifiable material adjacent to said pile and thereby forming a temporarily-stable shell around the removable pile, to provide a cavity for a permanent pile means for decreasing 50 the solidity of the surface of said shell contiguous to the pile and thereby facilitating the withdrawal of the pile, and means for filling the opening from which the pile is withdrawn and thus forming a permanent 55 pile.

As best seen in Fig. 2, the pile 1 is preferably formed with an internal lengthwise cavity 2, and is composed of a detachable point 3 and separable sections 4. The point 3 is generally formed with an internal chamber 5, 60 passages 6 leading laterally from the chamber 5 through the exterior surface of the point, and an opening 7 extending from said chamber through the upper face of the point 3 and communicating with an opening 8 65 leading downwardly from the cavity 2 through a lower end-surface of the lowest section 4 of the pile. The upper portion of the point 3 is reduced in diameter and frictionally engaged with the inner face of the lower 70 extremity of the lowest section 4, and the intermediate portion of the point 3 is provided with an annular shoulder 9 engaged with the lower edge of said section.

Contiguous surfaces of the point 3 and the 75 lowest section 4, may be united by any suitable soluble cement or adhesive material, unnecessary to illustrate and describe, which will be readily dissolved when the pile is within moist soil, and will not retard the separation of the lowest section 4 from the point 3, when the main part of the pile is withdrawn. Separation of said main part of the pile from the point 3 may also be facilitated 80 by providing the periphery of the point with 85 an annular groove 10, since the soil through which the point passes will enter this groove and resist the return or upward movement of the point 3 to a greater or less extent. The detachable point 3 closes the lower end of the 90 solidified or stable shell formed around the pile 1 and facilitates the support of said shell when the pile is withdrawn.

The sections 4 comprising the main part of the pile preferably taper downwardly, but 95 may obviously be of uniform diameter throughout if desired. Each section 4 is composed of a main portion and upper and lower divisions 11 12, secured to said main portion by suitable means, as screws 13, the 100 upper division 11 being provided with eyes 14 detachably secured to its periphery and having its inner face formed with lengthwise grooves or cutouts 15 arranged substantially 105 equidistant from each other and with inwardly-projecting threaded shoulders 16 alternating with the grooves or cutouts 15, and the lower division 12 having its periphery provided with lengthwise grooves or cutouts 17 arranged substantially equidistant from 110

each other and formed of sufficient size to receive the shoulders 16 of the opposing upper division 11 of the next lower section 4, and also having its periphery provided with projecting three-headed shoulders 18 movable lengthwise of the pile in the grooves or cutouts 15 in said opposing upper division, and then laterally into engagement with the shoulders 16 of said upper division. The section 4 provided with the point 3 is obviously not provided with a lower division 12, and the top of the uppermost section 4 is provided with a cap 19 formed with lengthwise grooves or cutouts and peripherally threaded shoulders 15 similar to the parts 17, 18 of the sections 12 for detachably securing said cap 19 to the top of the uppermost section 11. The described construction of my pile is particularly simple and effective, but it will be understood that any other suitable pile may be used with the remaining parts of my apparatus, and that said pile may either be of any predetermined length, or may be composed of sections detachably secured together by any desirable means.

The means for facilitating handling of the pile 1 may be of any suitable form, size and construction, and is here illustrated, Fig. 1, as a derrick 20 provided with a movable arm 21, winding means, as a drum 22, and any desirable movable supporting members, as chains 23, having means, as hooks 24, for detachably engaging the eyes 14. It will be understood, however, that the pile 1 may be handled by any other suitable means, and that if of small size, it may be manipulated by hand.

The means for forcing the pile 1 into the soil preferably comprises a float, as a boat or scow 25, a cylinder 26, a piston 27, and means for supplying a fluid under pressure to the cylinder. Said float 25 may be provided with a vertical opening, not illustrated, for the passage of the pile 1, or with a suitable framework 28, Fig. 2, for supporting said pile outside of the float, as in advance thereof. The cylinder 26 is fixed to the float 25, preferably by the framework 28, and the piston 27 is movable in the cylinder 26 and is connected to the pile 1. The means for supplying a fluid under pressure to the cylinder 26 usually comprises a tank 29 containing compressed air and a conduit 30 having branches for conducting the compressed air from the tank 29 to the lower and upper ends of the cylinder 26, said conduit 30 being provided with means, as valves 31, for controlling the flow therethrough. I generally use four of the cylinders 26 arranged equidistant from each other around the pile 1, and connect the pistons 27 to said pile by laterally-projecting arms 32 provided on the upper ends of the pistons 27 and detachably engaged with the upper face of the cap 19. The

tank 29 may be supplied with compressed air by any desirable means, as a pump 33, actuated by a rotary engine 34 connected to a steam-boiler 35.

If it is not convenient to handle the piles from a float and to force said piles downwardly by air-pressure, I support a suitable receptacle 36, Fig. 8, upon the upper portion of the pile, or the cap 19, and fill this receptacle with water, or soil, which may be withdrawn when it is desired to remove the pile.

The means for facilitating the entrance of the removable pile into the soil usually consists of a conduit 37 communicating with the chamber 5, and means for forcing a fluid under pressure through said conduit. As clearly seen in Fig. 2, the conduit 37 extends lengthwise of the cavity 2 and is composed of detachable sections of substantially the same length as the sections 4. The lower end of the conduit 37 is formed with a lower opening in its bottom face and with a series of upper openings above said face, Fig. 2, and is surrounded by a hollow valve 38 closely fitting the conduit and the openings 7, 8, and 9, having its lower end closed and its peripheral wall provided with upper and lower series of openings for communicating with the upper and lower openings in the conduit 37. The upper end of the conduit 37 projects above the pile 1 and its cap 19, and is detachably connected to conduits 39, 40. A rod 41 is connected to the valve 38 and extends lengthwise of the conduit 37 and outwardly through the upper closed end thereof, and is provided with any desirable engaging means in order that said rod may be readily moved for manipulating the valve 38. Said valve 38 is particularly applicable for use with the remaining parts of my apparatus, but it will be obvious that any other suitable valve may be employed in lieu thereof. The means for forcing a fluid under pressure through the conduit 37 consists of the tank 29 and the conduit 39 which is connected to said tank and is provided with means, as a valve 42, for controlling the flow through said conduit.

As best seen in Fig. 2, the means surrounding the upper portion of the pile 1 and containing a solidifiable material consists of a shell 43 of sufficient diameter so that a space is interposed between the inner face of said shell and the periphery of the pile. The lower end of the shell 43 enters the soil a limited distance, and the upper end thereof extends above the level of the water overlying the soil. Said upper end of the shell 43 may be engaged by the arms 32 just before the pile reaches the limit of its downward movement. The solidifiable material contained by the shell 43 is usually moist soil, and the upper surface thereof is above the water surrounding said shell 43. This material may

be filled into the shell 43 after the pile is in place by any desirable means, as a centrifugal pump, not illustrated.

The means for solidifying the soil and the solidifiable material around the pile consists of the cavity 2 and an artificial refrigerating apparatus for supplying a refrigerating agent to said cavity. The refrigerating apparatus may be of any suitable form, size and construction, and is here illustrated as a cooler or refrigerator proper 44, a compressor, or pump, 45 actuated by any desirable means, not shown, a condenser 46, an ammonia-receiving tank 47, a brine-reservoir 48, a conduit 49 for connecting the cooler 44 to the reservoir 48, and conduits 50 40 for respectively connecting the reservoir 48 and the cooler or refrigerator proper 44 to the cavity 2 and the conduit 37, the conduit 50 being also detachably connected to the cap 19, and said conduits 40 50 being respectively provided with valves 51 52. It will be understood that suitable means, as fans 53, may be utilized for maintaining a circulation of the refrigerating agent.

The means for decreasing the solidity of the surface of the stable shell surrounding the pile for facilitating withdrawal of the pile is here illustrated as consisting of the cavity 2, means for forcing the refrigerating agent from this cavity and means for discharging a heating agent, as steam, into the cavity. Said means for forcing the refrigerating agent from the cavity 2 consists of an air-conduit 54 leading from the tank 29 to the upper portion of the cavity 2 and detachably connected to the cap 19 and provided with suitable means, as a valve 55, for controlling the flow of the air. The means for discharging the heating agent, as steam, consists of the conduit 54, and a steam-pipe 56 communicating with a source of supply, as the boiler 35, and discharging into the conduit 54, said pipe 56 being provided with means, as a valve 57, for controlling the flow of the steam. As will be obvious to those skilled in the art, the extremity of the conduit 54 connected to the caps 19 and the corresponding extremities of the conduits 50 40 and 39 are flexible, or movable, to permit of the connection of these conduits to a cap 19, the ready disengagement of said conduits and their movement with the cap as the pile 1 descends.

The means for filling the openings from which the pile 1 is withdrawn, is here illustrated as a source of supply for cement 58, a movable chute 59 having an exit-opening 60, and a conveyer 61 for discharging the cement 60 through the opening 60. It will be understood, however, that the cement may be filled by hand within the opening from which said pile is withdrawn and that twisted metallic strips may be arranged in said opening 65 before the discharge of the cement thereto.

In order that it may be apparent that my invention is not limited to the detachable point 3 shown in Fig. 2, I have illustrated in Fig. 6 a point 62 fixed to the lowermost section of the pile and provided with a detachable shield, and in Fig. 7, a fixed point 63, the exit-passages 64 of which may be closed by a yielding valve 65 provided on the valve 38, but it will be understood that these are only two of the many possible modifications of the lower end of my movable pile. With the type of point shown in Fig. 7, the freezing agent may be discharged into the chamber of the point without liability of its escape through the passages 64.

In the operation of my apparatus, the shell 43 is placed in position, one or more sections 4 of the removable pile 1 are secured together, and the derrick 20 is operated to arrange said portion of the pile in the predetermined position and lower the same through the shell 43. Providing the pile descends into the soil by gravity, additional sections 4 may be added until said pile has penetrated the soil to the desired extent. In case force is required to cause the pile to enter the soil, a cap 19 of the requisite size is secured to the uppermost section 4, the conduits 39, 40, 50, 54, are detachably connected to the cap 19, and the arms 32 are detachably engaged with said cap. Air is then admitted to the upper ends of the cylinders 26, whereupon the pile is readily forced into the soil. After the descent of the pile, the conduits 39, 40, 50, 54 and the arms 32 are disengaged from the cap 19, said cap is removed, an additional section 4 is secured to the pile, and a second cap 19 is fastened to the upper end of the uppermost section 4 and is detachably connected to the conduits 39, 40, 50, 54 and detachably engaged by the arms 32. Additional sections 4 are secured to the pile in like manner from time to time until the same is of the requisite length. At any desired time during the entrance of the pile into the soil, the valve 38 is arranged in position to open communication from the conduit 37 to the chamber 5 of the point 3, the valve 42 is opened, and compressed air is discharged from the conduit 39 into the conduit 37; whence it flows through the chamber 5 and the passages 6 to the exterior of the point 3, thus facilitating the downward movement of the pile. After the pile has penetrated the soil to the predetermined depth, the flow of the compressed air is shut off by the valve 42, and the valve 38 is manipulated to close communication between the conduit 37 and the chamber 5, and to connect said conduit with chamber 2. Moist soil or other solidifiable material is filled within the shell 43 around the upper portion of the pile until the level of said soil is above the water surrounding the shell 43. The valves 51 52 are then opened, thus causing a circulation 30

of the refrigerating brine through the cavity 2 and the conduit 37 and freezing a comparatively stable shell around the pile. After the formation of said shell, the flow of the 5 brine from the conduit 50 is shut off by the valve 52 and the valve 55 is opened, whereupon compressed air forces the brine from the cavity 2 and through the conduits 37 40 to the cooler 44. Upon the discharge of the 10 refrigerating agent from the cavity 2, the valves 51 and 55 are closed, the valve 38 is manipulated to disconnect the conduit 37 from said cavity and steam is admitted to the cavity 2 from the conduit 54 and the pipe 15 56, thus melting the surface of the frozen or solidified shell immediately adjacent to the pile. The flow of the steam is then shut off, air is admitted to the lower ends of the cylinders 26 for relieving the pile from the weight 20 of the float, the pile is withdrawn by the derrick 20, and the solidified shell is filled with cement to the desired depth, thus forming a permanent pile. A number of these piles 25 may be inserted into the soil side by side and other foundations indicated by dotted lines in Fig. 9 placed thereupon. By measuring the amount of penetration of the removable pile and the quantity of cement used to form the permanent piles, it is possible to 30 35 form a plurality of piles of dissimilar length, but with their top surfaces in substantially the same plane which is a feature of great advantage. As will be obvious to those skilled in the art, the openings to which the 40 45 conduits 40, 50 and 54 are connected may be provided with caps, and in this event provided said caps are in place, it will not be necessary to connect said conduits 40, 50 and 54 to the caps until the pile has entered the 50 soil to the predetermined depth.

The construction and operation of my apparatus will now be readily understood upon reference to the foregoing description and the accompanying drawing, and it will be understood by those skilled in the art, that more or less change may be made in the component parts thereof without departing from the spirit of my invention.

Having thus fully described my invention, 55 what I claim as new and desire to secure by Letters Patent, is:—

1. In combination, a removable pile for entering the soil to provide a cavity for a permanent pile, said removable pile having an internal cavity, and means for supplying a refrigerating agent to the latter cavity to solidify the soil surrounding the removable pile and thereby preserve the wall of the permanent pile cavity after the withdrawal of 60 the removable pile, substantially as and for the purpose described.

2. In combination, a removable pile for entering the soil to form a permanent pile cavity, means for solidifying the soil adjacent to the pile and thereby forming a shell

around the pile, and means associated with said pile for loosening the pile from said shell to permit withdrawal of the same, substantially as and for the purpose set forth.

3. In combination, a removable pile for 70 entering the soil to provide a cavity for a permanent pile, means for decreasing the temperature of the removable pile and thereby solidifying the soil surrounding the pile and forming a shell around the same, and means for increasing the temperature of the removable pile and thereby melting the surface of said shell around the pile to permit withdrawal of said pile, substantially as and for the purpose specified.

4. In combination, a pile for entering the soil, said pile having an internal cavity and having its point formed with a passage communicating with the cavity and leading through the exterior surface of the point, 85 means for supplying a fluid to the cavity, and means associated with the pile for preventing the escape of said fluid through the passage, substantially as and for the purpose specified.

5. In combination, a pile for entering the soil, said pile having its point formed with a passage leading through the exterior surface of the point, a conduit associated with the pile and communicating with the passage, 95 and means associated with the pile for preventing the communication of the conduit with the passage, substantially as and for the purpose described.

6. In combination, a pile for entering the 100 soil, said pile having its point formed with a chamber and a passage leading from the chamber through the exterior surface of the point, a conduit associated with the pile and communicating with the chamber, and means associated with the pile for preventing the communication of the conduit with the chamber, substantially as and for the purpose set forth.

7. In combination, a pile for entering the 110 soil, said pile having an internal cavity and having its point formed with a passage leading through the exterior surface of the point, a conduit arranged in the internal cavity and having means for communicating with the 115 cavity and with said passage, means for supplying a fluid to the cavity and the conduit, and means for preventing the communication of the conduit with the passage, substantially as and for the purpose specified.

8. In combination, a removable pile for entering the soil to provide a cavity for a permanent pile, means for decreasing the temperature of the removable pile and thereby solidifying the soil surrounding the pile 125 and forming a shell around the same, means for increasing the temperature of the removable pile and thereby melting the surface of said shell around the pile to permit withdrawal of said pile, and means supported by 130

the pile for controlling the means for increasing and decreasing the temperature thereof, substantially as and for the purpose specified.

9. In combination, a pile for entering the soil, said pile having an internal cavity, means for supplying a refrigerating agent to the internal cavity, and means within the cavity for controlling the passage of said refrigerating agent, substantially as and for the purpose set forth.

10. In combination, a pile for entering the soil, said pile having an internal cavity and having its point formed with passages communicating with the cavity and leading through the exterior surface of the point, means for forcing a fluid under pressure through the passages and thereby facilitating the entrance of the pile into the soil, and means for supplying a refrigerating agent to the internal cavity, substantially as and for the purpose described.

11. In combination, a pile for entering the soil, said pile having an internal cavity and having its point formed with a chamber and passages leading from the chamber through the exterior surface of the point, means for forcing a fluid under pressure into the chamber and through the passages and thereby facilitating the entrance of the pile into the soil, and means for supplying a refrigerating agent to the internal cavity, substantially as and for the purpose specified.

12. In combination, a pile for entering the soil, said pile having an internal cavity and having its point formed with passages leading through the exterior surface of the point, means for forcing a fluid under pressure through the passages and thereby facilitating the entrance of the pile into the soil, means for supplying a refrigerating agent to the internal cavity, and means for preventing the passage of the refrigerating agent from the internal cavity to the passages of the point, substantially as and for the purpose set forth.

13. In combination, a pile for entering the soil, said pile having an internal cavity, a conduit extending lengthwise of the pile and having an opening for communicating with the cavity, and means for opening and closing communication between the cavity and the conduit, substantially as and for the purpose described.

14. In combination, a pile for entering the soil, said pile having an internal cavity and having its point formed with passages leading through the exterior surface of the point, a conduit extending lengthwise of the pile within the cavity and having an opening for communicating with the passages, means for forcing a fluid under pressure through the conduit and the passages and thereby facilitating the entrance of the pile into the soil, means for supplying a refrigerating agent to the internal cavity, and means for prevent-

ing communication between the internal cavity and the passages and for preventing the flow of the fluid under pressure from the passages, substantially as and for the purpose described.

15. In combination, a pile for entering the soil, said pile being provided with a removable point, and means for solidifying the soil surrounding the pile above the point, substantially as and for the purpose specified.

16. In combination, a pile for entering the soil, said pile being provided with a removable point formed with a chamber and an opening extending from the chamber through an upper face of the point, and means for solidifying the soil surrounding the pile above the point, substantially as and for the purpose set forth.

17. In combination, a pile for entering the soil, said pile being provided with an internal cavity and with a removable point formed with a chamber, passages leading from the chamber through the exterior surface of the point, and an opening extending from the chamber through an upper face of the point and communicating with the cavity, a conduit for communicating with the chamber, means within said opening for controlling the communication between the conduit and the chamber, means for supplying a fluid under pressure through the conduit, the chamber and the passages and thereby facilitating the entrance of the pile into the soil, and means for supplying a refrigerating agent to the cavity for freezing the soil around the pile above the removable point, substantially as and for the purpose described.

18. In an apparatus for making openings in submerged soil and the overlying liquid, the combination of a pile, a shell surrounding the portion of the pile within the liquid and having its inner face separated from the pile for forming a space to receive a solidifiable material, and means for solidifying the surface of the soil and said material surrounding the pile and forming a shell around the pile, substantially as and for the purpose specified.

19. In an apparatus for making openings in submerged soil and the overlying liquid, the combination of a pile having an internal cavity, a shell surrounding the portion of the pile within the liquid and having its inner face separated from the pile for forming a space to receive a material solidifiable by freezing, and means for supplying a refrigerating agent to the cavity and thereby freezing the soil adjacent to the pile and also said solidifiable material and forming a shell around the pile, substantially as and for the purpose set forth.

20. In an apparatus for making openings in submerged soil and the overlying liquid, the combination of a pile having an internal cavity, a shell surrounding the portion of the

- pile within the liquid and having its inner face separated from the pile for forming a space to receive a material solidifiable by freezing, means for supplying a refrigerating agent to the cavity and thereby freezing the soil adjacent to the pile and also said solidifiable material and forming a shell around the pile, and means for supplying a heating agent to the cavity of the pile for melting the surface of said shell contiguous to the pile and thereby permitting withdrawal of the pile, substantially as and for the purpose described.
21. In an apparatus for forcing piles into submerged soil, the combination of a pile, a float, and means associated with the float for causing movement of the pile in reference to the float whereby the weight of the float acts to force the pile into the soil, substantially as and for the purpose specified.
22. In an apparatus for forcing piles into submerged soil, the combination with two members, one comprising a pile and the other a float; of a cylinder connected to one of said members, a piston movable in the cylinder and connected to the other member, and means for supplying a fluid under pressure to the cylinder, substantially as and for the purpose set forth.
23. In an apparatus for forcing piles into submerged soil, the combination with two members, one comprising a pile and the other a float; of a cylinder connected to the float, a piston movable in the cylinder, an engaging member connected to the piston and movable into engagement with the pile, and means for supplying a fluid under pressure to the cylinder, substantially as and for the purpose described.
24. In an apparatus for forming piles in moist soil, the combination of a pile for entering the soil, means for forcing the pile into the soil, means for solidifying a shell around the pile, means for withdrawing the pile from said shell, and means for filling cement into said shell, substantially as and for the purpose described.
25. The herein described process of making openings in unstable soil, the same consisting in forcing a pile into the soil, solidifying the surface of the soil adjacent to the pile and thereby forming a shell around the pile, and finally withdrawing the pile from said shell, substantially as and for the purpose specified.
26. The herein described process of making openings in unstable soil, the same consisting in forcing a pile into the soil, freezing the surface of the soil adjacent to the pile and thereby forming a shell around the pile, and finally withdrawing the pile from said shell substantially as and for the purpose set forth.
27. The herein described process of making openings in unstable soil, the same consisting in forcing a hollow pile into the soil,
- subjecting the surface of the soil adjacent to the pile to the influence of a refrigerating agent within the interior of the pile and thereby forming a shell around the pile, and finally withdrawing the pile from said shell, substantially as and for the purpose set forth.
28. The herein described process of making openings in unstable submerged soil and the superimposed liquid, the same consisting in forcing a pile into the soil, surrounding the portion of the pile within the liquid with a solidifiable material, solidifying the surface of the soil and of said material adjacent to the pile and thereby forming a shell around the pile, and finally withdrawing the pile from said shell, substantially as and for the purpose described.
29. The herein described process of making openings in unstable soil, the same consisting in forcing the soil from the lower end of the pile and thereby facilitating the entrance of said end into the soil, solidifying the surface of the soil adjacent to the pile and thereby forming a shell around the pile, and finally withdrawing the pile from said shell, substantially as and for the purpose specified.
30. The herein described process of making openings in unstable soil, the same consisting in forcing a pile into the soil, solidifying the surface of the soil adjacent to the pile and thereby forming a shell around the pile, decreasing the solidity of the surface of said shell contiguous to the pile, and finally withdrawing the pile from said shell, substantially as and for the purpose described.
31. The herein described process of making openings in unstable soil, the same consisting in forcing a hollow pile into the soil, subjecting the surface of the soil adjacent to the pile to the influence of a refrigerating agent within the interior of the pile and thereby forming a shell around the pile, subjecting the surface of said shell contiguous to the pile to the influence of a heating agent within the interior of the pile, and finally withdrawing the pile from said shell, substantially as and for the purpose specified.
32. The herein described process of making piles in unstable soil, the same consisting in forcing a pile into the soil, solidifying the surface of the soil adjacent to the pile and thereby forming a shell around the pile, withdrawing the pile from said shell, and inserting a filler into said shell, substantially as and for the purpose set forth.

In testimony whereof, I have hereunto signed my name in the presence of two attesting witnesses, at Syracuse, in the county of Onondaga, in the State of New York, this 31st day of October, 1903.

GEORGE G. HAYER.
